NO. 12.165

FEB 15, 1881

UNITED STATES PATENT OFFICE.

OLIVER B. KEELEY, OF SPRING CITY, AND JAMES M. ATCHISON, OF PHILADELPHIA, PENNSYLVANIA, ASSIGNORS TO SAID KEELEY.

DESIGN FOR A RANGE.

SPECIFICATION forming part of Design No. 12,165, dated February 15, 1881.

Application filed January 18, 1881. Term of patent 7 years.

To all whom it may concern:

Be it known that we, OLIVER B. KEELEY, a citizen of the United States, residing in Spring City, Chester county, Pennsylvania, and JAMES M. ATCHISON, a citizen of the United States, residing in Philadelphia, Pennsylvania, have invented a new and original Design for a Range, of which the following is a specification.

Our design is fully shown in the accompanying drawing, which represents a perspective view of the range.

The main oven-door is oblong, and has a central oblong panel, *a*, the face of which bears the title of the stove, and the edges of which are beveled. The face of the door has line-work ornamentation following the outline of the door, and elaborated at the corners into ornaments *b*, and outside of this is a flat border, *d*, with corner ornaments *e*, the door being furnished with a beveled and ornamented edge, *f*.

The fire-door has a beveled and ornamented edge, *g*, flat border *h*, with corner ornaments and five mica panels, *i*, shaped and arranged as shown. The ash-door has a border, *m*, and a central panel, *n*, with foliated ornamentation.

The end plate of the range has the paneled ash-pit slide *s*, and is ornamented with a central panel, *w*, and corner ornaments *x*.

We claim—

1. The design for the oven-door, said design comprising the central panel, *a*, corner ornaments *b*, border *d*, and ornamented edge *f*, as shown and described. 35

2. The design for the fire-door, said design comprising the five mica panels *i*, shaped and arranged as shown and described.

3. The design for the fire-door, said design comprising the five mica panels *i*, beveled outer edge, *g*, and flat border *h*, as shown and described. 40

4. The design for the ash-door, said design comprising the border *m*, and central panel, *n*, with foliated ornamentation, as shown and described. 45

5. The design for the stove, said design comprising the oven-door, fire-door, ash-pit door, end ash-pit slide, and end ornamentation *w x*, as shown and described. 50

In testimony whereof we have signed our names to this specification in the presence of two subscribing witnesses.

OLIVER B. KEELEY.
JAMES M. ATCHISON.
